CLAIM

The ornamental design for a fishing bobber, as shown and described.

DESCRIPTION

FIG. 1 is a perspective view of the fishing bobber showing my new design;

FIG. 2 is a right side elevation view thereof, the left side elevation not shown being a mirror image of the side elevation shown;

FIG. 3 is a front end elevation view thereof;

FIG. 4 is a rear end elevation view thereof;

FIG. 5 is a top plan view thereof; and,

FIG. 6 is a bottom plan view thereof.
